UNITED STATES PATENT OFFICE.

EMIL DEISTER, OF FORT WAYNE, INDIANA, ASSIGNOR TO THE DEISTER CONCENTRATOR COMPANY, A CORPORATION OF INDIANA.

ORE-CONCENTRATING TABLE.

No. 895,734.

Specification of Letters Patent.

Patented Aug. 11, 1908.

Application filed March 1, 1906. Serial No. 303,585.

To all whom it may concern:

Be it known that I, EMIL DEISTER, citizen of the United States of America, and resident of Fort Wayne, in the county of Allen and State of Indiana, have invented certain new and useful Improvements in Ore-Concentrating Tables, of which the following is a specification.

This invention relates to improvements in ore-concentrating tables, and the object thereof is to provide a table so proportioned and shaped, with means in connection therewith which will direct the discharge of mineral therefrom as the same becomes clean; and also to effect the movement of overlying gangue at a broad angle from that in which the underlying mineral moves.

My object is accomplished by the construction illustrated in the accompanying drawings in which

Figure 1 is a perspective view showing my improved concentrating table and the particular arrangement of riffles thereon; Fig. 2 is a plan view showing the rhomboidal form of the table, the relation of the driving mechanism in connection therewith, and the arrangement of the riffles; and Fig. 3 is a sectional view of the table in a vertical plane adjacent to and parallel with the breast board, showing the relative heights of the riffles.

Similar numerals of reference indicate corresponding parts in both views, and referring now to the same: 1 is a concentrating table of rhomboidal form, the length of which is approximately double that of its width, and which has a head-board 2 at one end and a breast-board 3 projecting along one of its sides. The concentrating surface of the table is of suitable material, such as linoleum, and ranges in a flat plane throughout, except at the outer edge of the table at a point immediately adjacent the head-board where the linoleum cover 4 is held in a raised position by means of a wedge 5 which is inserted thereunder. A feed box 6 is secured to the head-board 2 and overhangs the surface of the table adjacent thereto.

It is the intention that the table shall have differential reciprocating movement in a line parallel with its ends, and suitable driving mechanism 7 is arranged in connection therewith to impart thereto the desired lateral motion.

The table is suitably mounted by any well known means, and when in proper position

for use ranges upon a decline from its end at the head-board to its opposite or tailings discharge end, and also upon lateral incline from the breast-board side to its opposite or mineral discharge side. At the lower end of the table are arranged a tailings launder 8 and middlings launder 9, and along the mineral discharge side of the table, beneath the corresponding edge thereof, is arranged a mineral launder 10 to receive the discharged mineral therefrom.

A particular feature of this invention is the form and arrangement of the table in connection with the particular arrangement and character of riffles 11 thereon: The riffles are all relatively parallel and are arranged laterally upon the table or parallel with the ends thereof. Each riffle tapers from its inner end at the breast-board to a thin edge at its outer end, but the successive riffles, from the head-board to the tailings discharge end of the table, gradually decrease in height and project accordingly less from the corresponding surface of the table along the breast side thereof. It will therefore appear that the projection of the riffles at the upper end of the table is greater than those at the tailings discharge end thereof, except that the riffles taper to a uniform height at their outer ends. These riffles are arranged in successive parallel series 12, 13, 14, and 15 respectively, the end riffle 16 of each series being of greater length than the other riffles and extending to the mineral discharge edge 17 of the table. The other riffles of the several series terminate upon the surface of the table at points suitably distant from the mineral discharge edge 17 and thereby are provided long unriffled washing surfaces 18, each of which is separated from the adjacent washing surface by the outer extensions of the respective long riffles 16.

In the operation of this invention the table is set in rapid differential oscillating motion laterally, and ore pulp is fed into the feed box from whence it passes onto the adjacent surface of the table. Because of the longitudinal decline of the table, the pulp will move lengthwise thereon to the lower end thereof, and because of the differential motion and lateral incline of the table, together with the riffles, the mineral portion of the pulp will be directed from beneath the pulp out upon the washing surfaces where it may be treated to the action of dressing water supplied in any

suitable manner. The extending long riffles direct the cleaned mineral from the corresponding washing surfaces to the mineral discharge edge 17 of the table from whence it 5 gravitates into the mineral launder. By this arrangement the partially concentrated mineral is treated in several masses, each of which is local to the corresponding washing surface and adjacent series of riffles. Thus 10 it will appear that the mineral is discharged from the table as the same becomes cleaned and does not follow along the margin of the body of pulp as is commonly the case.

A feature of this invention is that the table 15 is made rhomboidal and is actuated in a line parallel with its ends, and it should appear that the lower end of the table extends farther out in the direction of its motion than the upper end thereof, so that the surface 20 of the table ranges more or less in line with the tendency of movement of the body of pulp, viz: The pulp has a tendency to move at right angles to the line of motion because of the longitudinal decline of the table, and 25 to a more or less extent in line with the motion of the table because of the differential action, and hence the movement of pulp is somewhat diagonal to the line of motion of the table. Another feature of this invention 30 is the gradual decrease in the height of the successive riffles toward the lower end of the table. The riffles thus arranged have the effect of relieving the overlying gangue so that the latter tends to move at a broad 35 angle toward the lower end of the table away from the washing surfaces. This effects more perfect separation of the underlying mineral from the overlying gangue than where the angle of movement between 40 the underlying mineral and overlying gangue is less.

The form and arrangement of the table proper herein set forth is similar to that shown in a previous application filed by me 45 Feb. 19, 1906, Sr. No. 301,728, but is distinguished therefrom particularly by the arrangement of riffles. The table in the present instance is provided with riffles arranged especially for grades of pulp coarser 50 than slimes.

Having described my invention, what I claim as new and desire to secure by Letters Patent is:

1. In a device of the class described, a 55 reciprocating table having a projecting

breast-board at its rear side; and parallel riffles upon the table arranged in similar successive groups, the end riffle of each group being of greater length than the other riffles and extending from the breast-board 60 to the mineral discharge edge of the table, the other riffles being substantially of uniform length, all of which commence their course at the breast-board and terminate at points suitably distant from the mineral 65 discharge edge of the table, there being a washing surface along the mineral discharge edge adjacent each group of riffles, said washing surfaces being separated from one another by the respective end riffles, all of 70 said riffles being tapered toward their outer ends, there being a uniform decrease in the height of the respective riffles at corresponding points successively toward the tailings discharge end of the table. 75

2. In a device of the class described, a reciprocating table having a projecting breast-board along its rear side; and a series of parallel riffles arranged upon the table in similar groups, the end riffle of each group 80 being of greater length than the other riffles and extending from the breast-board to the mineral discharge edge of the table, the other riffles extending from the breast-board and terminating at points suitably distant 85 from the mineral discharge edge, there being a washing surface along the mineral discharge edge adjacent each group of riffles, the washing surfaces being separated from one another by the respective end riffles. 90

3. In a device of the class described, a reciprocating table having a projecting breast-board along its rear side, and having also parallel riffles arranged in similar groups, the end riffle of each group extending from 95 the breast-board to the mineral discharge edge of the table, and the other riffles extending from the breast-board to points suitably distant from the mineral discharge edge, there being a uniform decrease in the height 100 of the respective riffles at corresponding points successively toward the low end of the table.

In testimony whereof I affix my signature, in presence of two witnesses.

EMIL DEISTER.
